UNITED STATES PATENT OFFICE

2,267,922

COMB CLEANER

James F. Hunter, Turtle Creek, Pa.

Application July 17, 1940, Serial No. 345,972

2 Claims. (Cl. 132—29)

This invention relates to new and useful improvements in comb cleaners, and it is among the objects thereof to provide a comb cleaner in which a stranded fabric is mounted on a support in a manner to make it readily removable and renewable without the need for any clamping or adjusting means.

The invention will become more apparent from a consideration of the accompanying drawing constituting a part hereof in which like reference characters designate like parts and in which:

Fig. 1 is a view in perspective of a comb cleaner support embodying the principles of the invention;

Fig. 2 is a comb cleaning element of stranded fabric; and

Fig. 3 is a top plan view illustrating the manner of application of the cleaning element to the support.

In the drawing, the numeral 1 designates a U-shaped base 1 of any suitable material such as a molded resinous compound which may be rigid or springy in character, the base having a handle 2 and upstanding bridge-like elements 3, which are slotted at 4 for receiving looped ends 5 of a stranded fabric material, having individual strands 6 extending between the loops.

The cleaner is mounted on a support by inserting one end of the loop in the biased slot 4 in the manner shown in Fig. 3, gathering all of the material of the loop on one side of the slot as shown. The loop fabric is then leveled out on the bridge 3, as shown at one end of Fig. 3 to stretch across the span of the bridge. When assembled, the strands will be stretched horizontally, as shown in Fig. 2, across the end bridges

3. If the material of the base 1 is flexible, the

base may be flexed when the fabric material is mounted thereon, so that when released, the strands 6 will be taut.

From the foregoing description of the drawing it is apparent that the tooth cleaning strand material can be speedily and conveniently assembled on the base without any difficulty and without any clamps and because of the simplicity of renewing the cleaning element, such devices would be of such practicability as to warrant their more general adoption.

Although one embodiment of the invention has been herein illustrated and described, it will be evident to those skilled in the art that various modifications may be made in the details of construction without departing from the principles herein set forth.

I claim:

1. A comb cleaner comprising a base member having a pair of bridge-like members upstanding thereon, said bridge members having slots therein for receiving the looped ends of a stranded fabric element and said slots having their walls overlapping to constitute a substantially continuous support for the looped fabric, whereby said looped ends are stretched across the bridge members and the connecting strands extend from bridge to bridge.

2. A comb cleaner comprising a substantially flat U-shaped member having the parallel upright portions cut-out to form a bridge, the bridges of said elements having angularly disposed slots to receive the looped ends of strands of fabric for stretching the strands between the bridge members.

JAMES F. HUNTER.
